(57) **CLAIM**

The ornamental design for a squeezable leak proof feeding bottle, as shown and described.

DESCRIPTION

FIG. 1 is a front elevational view of the squeezable leak proof feeding bottle.

FIG. 2 is a back elevational view of the squeezable leak proof feeding bottle.

FIG. 3 is a right side elevational view of the squeezable leak proof feeding bottle.

FIG. 4 is a left side elevational view of the squeezable leak proof feeding bottle.

FIG. 5 is a top plan view of the squeezable leak proof feeding bottle.

FIG. 6 is a bottom plan view of the squeezable leak proof feeding bottle.

FIG. 7 is a front perspective view of the squeezable leak proof feeding bottle showing the feeder cap open as in use for feeding; and,

FIG. 8 is an exploded perspective view of the squeezable leak proof feeding bottle showing the feeder disassembled as for cleaning.
